INVENTOR
Frederick J. Dowling

UNITED STATES PATENT OFFICE.

FRANCIS J. DOWLING, OF NEW YORK, N. Y.

TWEEZERS.

Application filed October 14, 1927. Serial No. 226,184.

This invention relates to tweezers and similar devices for removing hairs and the like, and has for one of its objects the provision of an improved tweezers having means to stretch the skin at said hair.

A further object of the invention is to provide an improved hair tweezers having means for automatically retracting same to remove a hair, and means to press or stretch the skin away from said hair.

A further object of the invention is to provide an improved hair tweezers that permits practically painless removal of a hair, and with a maximum of safety, and which can be worked with the greatest rapidity and ease by the operator, and is comparatively inconspicuous in its action.

A further object of the invention is to provide an improved hair tweezers freely mounted for movement on supporting means, so that said tweezers can move rearward on unintended contact of the tweeler jaws with said skin.

A further object of the invention is to provide a tweezers having improved means for retracting same to remove a hair.

A further object of the invention is to provide improved means for stretching the skin at a hair to facilitate the removal of said hair by a tweezers.

A further object of the invention is to provide an improved tweezers, or the like, having skin stretching or pressing means which can be actuated independently of the operation of the tweezers, so that the skin may be stretched or pressed to any desired extent.

A further object of the invention is in the provision of an improved tweezers having skin stretching or pressing means that produce a maximum stretching or pressing action at the instant of retraction of the hair.

A further object of the invention is to provide an improved tweezers having skin stretching or pressing means operative as a unit with the tweezers for maximum celerity and ease of the operator, and which are also separately operative if desired to permit the judgment of the operator to suit varying conditions.

A further object of the invention is to provide an improved tweezers having skin stretching means, or other means, as set forth, wherein in the actuation of said tweezers is caused by a movement of the operator's hand toward the skin acted upon, this particularly facili-

tating the operation of the instrument and the accomplishment of the objects herein set forth.

It is to be understood that while the term tweezers is used herein yet the invention may clearly embrace devices of other types, such, for instance, as blackhead removers. Furthermore that said skin stretching means have necessarily a pressing action against the skin, and contact same, in the manner of a supporting or guiding means for the tweezers or other device. These different relations are more definitely set forth in the following claims.

Other objects will in part be obvious and in part pointed out hereinafter.

The drawing illustrates a possible embodiment of the invention, the scope whereof will be indicated in the claims.

Figure 1 is a view in elevation, with a part broken away, of a tweezers embodying the invention.

Figure 2 is an enlarged fragmentary view of certain details.

Figures 3, 4 and 5 are enlarged fragmentary, diagrammatic views of cam mechanism in different positions.

Figure 6 is a view in elevation of an embodiment of the invention illustrating a modification, with parts in section.

Figures 7 and 8 are fragmentary views in section of details of said modification in different positions of operation.

Figure 9 is a view of certain details of invention taken on line 9—9 of Figure 6.

Figure 10 is a view in elevation, with parts in section, of a modification of the invention.

Figure 11 is a view in section taken approximately on line 11—11 of Figure 10.

Figure 12 is an enlarged fragmentary view of a detail.

Figure 13 is a sectional view on line 13—13 of Figure 10.

Figure 14 is a view similar to Figure 13 but with the tweezers closed.

Referring in detail to the drawings, 15 denotes a tweezers embodying the invention. Said tweezers is seen to comprise a tweeler member 16 having a pair of side portions 17 connected together at their upper ends and terminating at their lower ends in jaws 18. Said tweeler member 16 is mounted on a supporting frame 19 including a pair of upright members or guides 20, to which is secured a handpiece 21. The tweeler arms 17 extend

along the frame members 20, preferably in parallel relation thereto, and the tweezer member is movable along said frame 19. For this purpose, the guide bars 20 may be provided with upper and lower slots 22 and 23 through which each tweezer arm extends in opposite directions, thereby interlocking the tweezer member and said frame. The length of the slots 22 and 23, however, permits the desired relative vertical movement of the tweezer member on said frame. A compression spring 24 acting between the finger piece 21 and the upper portion of the tweezer member 16 retains said tweezer member in its downward position. However, since the proportion of the parts is such that said tweezer member is free to move laterally, as shown in Figure 1, said tweezer member constitutes a floating device which can readily be adjusted or moved to desired position, against the stabilizing force of the spring 24.

Associated, or separately mounted skin stretching means 25 are provided, to stretch the skin, preparatory to removing a hair. Preferably said means consist of a plurality of depending fingers 26 which are pivotally mounted on the guide bars 20 at 27. Said fingers are provided with friction shoes 28, which may be of rubber, and replaceable. The ends of said fingers are normally below the jaws 18, thus forming a spacing means, permitting the tweezers to be properly directed and protecting the skin against injurious or unintended contact of the tweezer jaws with said skin. Further safeguard in this respect is provided in that the spring 24 is so weak as to permit the tweezer member to readily recede along the support 19 on unintended contact with the skin.

The fingers 26 are inclined with their lower ends away from each other, so that on exerting downward pressure on said fingers at points 27, in any convenient manner, for instance, at 21, said shoes 28 will be caused to move apart from each other, while the arms 26 pivot in opposite directions. Thus the skin about a hair or splinter, can be effectively stretched. Simultaneously, the support 19 and tweezer member 16 are lowered so that the tweezer jaws 18 are substantially in contact with the skin. The tweezer member can now be manually closed and retracted to remove the hair, and since the tweezer arms 17 are external of the support 19, this can be conveniently accomplished.

The skin stretching means serve to render a hair, or the like, more easily accessible for inspection, and removal, particularly if said hair is in a scar, or other out of the way place. They furthermore exert a downward pressure on the skin, so as to facilitate removal of the hair, and render same practically painless, since the skin is not pulled upward itself on removing the hair. By forming the shoes 28 of arcuate or cam for-

mation, said shoes may press down on the skin in close and constant proximity to said hair, since there is a rolling action of the shoes toward said hair.

For automatic closing of the tweezer member, and retraction of same to remove a hair, cam mechanism 29 is provided, actuated by the fingers 26, through the pivotal movement thereof. There is a cam unit at each side of the tweezers, so that both sides of the tweezer member are actuated simultaneously. Each unit includes on finger 26 a vertically acting follower 30 and a laterally acting follower 31, for the cams 32, 33, 34 and 35 on the tweezer member. Each cam unit thus extends and is movable through a slot 23, and the follower 30 of each unit acts on cam 32 to support the tweezer member 16 against downward movement by the spring. The follower 31 of each unit closes the tweezer jaws by acting on cam 33 to cause a movement of the cam actuated portions 36 as shown by arrow A of Figure 4. While the tweezers is closing the follower 30 moves along the cam 32, which is formed with the axis at 27 as a center. In this way the tweezer member is supported at constant elevation relative to support 19. The follower 30 then rides along cam 34 to elevate the tweezer member 16, as shown by arrow B in Figure 5, so as to automatically remove the hair. While the tweezer member is being elevated, follower 31 rides along the cam 35, which is offset inward so as to provide the space required by the follower 31 and to retain the tweezers closed. But the degree of skin stretching action can be varied, since the construction of the tweezers permits less stretching action to be exerted by reducing the extent of downward movement of the support 19, and the tweezers will nevertheless be retracted sufficiently to remove the hair.

The fingers 26 may be made of integral construction with said followers, and tongues 37 struck therein engage the pintles 27 to pivotally mount said fingers thereon.

To adjust the normal or initial elevation of tweezer member 16 relative to support 19, a thumbscrew 38 at the top of said member is operative to increase the compression on spring 24. This will cause a slight flexure in the follower support 39 and a consequent downward movement of the tweezer member relative to said support.

To provide a balanced initial position of the fingers 26, the tweezer portions 36 are formed with abutment portions 40 limiting inward movement of the lower ends of said fingers.

In Figures 6 to 9 is shown a modification of the invention, in which a support 41 is provided for a tweezer member 42. The support includes a handpiece 43 having threaded shank portions 44 and 45 bearing locknuts 46, 47. Mounted on said shank portions 44, 45 is a frame 48 and a tweezer member 49. A

spring 50 in shank 44 is positioned between the upper end portions 51, 52 of said frame and said tweezer member, and a spring 53 on the same shank acts between nut 47 and 5 said portion 52 of said tweezer member.

The lower ends of the frame 48 are outwardly bowed at 54 and provided with removable rubber shoes 55, which are normally beneath the jaws 56 of the tweezer member. By exerting pressure on the support 41, the skin is stretched and the tweezer jaws approach the skin. The tweezer member may, however, be actuated by finger pieces 57 formed on said member adjacent to the jaw, so that the member can be moved vertically, or laterally, or closed independently of said support. It may be understood, however, that these features may be used in conjunction with one another.

20 For automatic closing and retraction of the tweezer member, the latter is bowed at each side to provide cams 58 and 59 which are received in slots 60 in the frame 48. A collar 51 vertically movable on said frame, on being moved downward by the hand of the operator engages cams 58 to move the tweezer member downward and likewise to close same. Meanwhile cams 59 engage the lower ends of slots 60 to move the bowed portions 30 54 outward to cause the shoes to stretch the skin. Figure 7 illustrates the position at the end of such movement, the collar 51 being now engaged over the ends of cams 58. Spring 53 is now effective to retract the 35 tweezer member, with the cam 58 clearing said collar, which however, retains the tweezers closed during retraction. Figure 8 illustrates the position after retraction of the tweezer member, and on moving the collar 40 upward, the device is restored to the position shown in Figure 6. The skin stretching action will be seen to increase to a maximum at the instant of retraction.

The cam portions 58, 59 may of course, be 45 engaged directly by the hand of the operator for closing of the tweezers or retraction of same, as is clearly apparent from the construction, and may be operated independently of the skin stretching means, as the latter 50 can be actuated solely by downward pressure.

The great convenience of the invention in its various forms is seen in that actuation 55 may be caused by a downward movement toward the skin. Moreover the body of the instrument can be held in the hand, and manipulation afforded by the fingers of the same hand.

Figures 10 to 14 illustrate a further modification of the invention, in which a support 65 60 is provided for a tweezer member 66 having jaws 67 spaced from the skin by the rubber shoes 68. The legs 69 of said support are curved in cross section to receive collar 70 for angular movement. The arms of tweezers 65 66 are provided with legs 71 engaging in

openings or slots 72 formed in the legs 69 and slightly projecting therethrough. Said arms are formed with projections 73 adapted to be engaged by similar projections or lugs 74 formed on collar 70 when the collar 70 is moved angularly, so as to effect the closing of the tweezers. In normal or initial position, the collar 70 is above the projections 73. On moving said collar downward, it engages the lugs 71 and depresses the tweezer member 66 75 till the jaws come adjacent to the skin. The collar 70 is then moved angularly to close the tweezers. The projecting ends of the lugs 71 will now terminate within the outer surface of the legs 69, owing to the convexity of said 80 legs, so that the lugs 71 will be released from the collar. The tweezer member will now be retracted by the spring 75. During such retraction the projections 74, 75 are in engagement to retain the tweezers closed. The collar 85 is then turned to the right or the left to permit the tweezers to open, and raised to initial position as shown in Figure 10. The operation described may be independent of or in conjunction to any desired extent with the 90 skin stretching means.

I claim:

1. Mechanism comprising a device to act on a particle on a skin, and coaxial means including relatively movable jaws to stretch 95 said skin at said particle.

2. A device comprising a hair tweezers, and simultaneously coacting means including jaws movable apart to press the skin laterally 100 from the hair.

3. Mechanism comprising a device to remove a particle from a skin, and angular movable means coacting with said device, said means having shoes to engage the skin to stretch same at said particle, said shoes being curved for a rolling action on the skin. 105

4. Means to stretch the skin about a hair, said means having relatively movable frictional skin engaging shoes, said means being actuated by pressing the same toward the 110 skin, for the purpose set forth.

5. Mechanism comprising a device to remove a particle from a skin, fingers engaging the skin at said particle and spacing the device from said skin, and means engaging said fingers and said device so that said device can be moved downward to the skin, and said fingers simultaneously spread to stretch the 115 skin.

6. Mechanism comprising a tweezers, skin stretching means, a support for said tweezers including jaws movable apart, and means to retract said tweezers relative to said support. 120

7. In mechanism of the character described, a tweezers, skin stretching means associated therewith, a support for said tweezers, and means to close the tweezers and retract same relative to said support. 125

8. Mechanism comprising a tweezers, and means supporting the tweezers for rearward 130

- movement of the same on unintended contact of the jaws of the tweezers with the skin.
9. In mechanism of the character described, a tweezers, skin stretching means, and unitary means for simultaneously closing the tweezers and actuating said stretching means.
10. In combination, a device for removing a particle from a skin, skin stretching means, and means to actuate said device and said skin stretching means, for a variable amount of skin stretching action by the latter.
11. In mechanism of the character described, a tweezers to remove a hair, a support for said tweezers including jaws movable apart, and means mounted on the support to close the tweezers.
12. In mechanism of the character described, a tweezers, skin stretching means, and means actuated toward the tweezer jaws to cause the first-mentioned means to function and to bring the tweezer jaws close to the skin.
13. In mechanism of the character described, a tweezers to remove a hair, skin stretching means, other means movable in a plane transverse to the tweezers to close the same, and means coacting with the skin stretching means to retract the tweezers.
14. In mechanism of the character set forth a tweezers, a support for the tweezers resting on the skin, and cam means carried by the support and coacting with the tweezer arms to close the tweezers.
15. In mechanism of the character set forth a tweezers to remove a hair, means to contact the skin at said hair, and means coacting with and movable with respect to the first mentioned means to close the tweezers.
16. In combination, a device to remove a particle from a skin, and movable jaws to press on the skin at said particle at variable distances apart about the particle and to stretch the skin.
17. In mechanism of the character set forth, a tweezers to remove a hair, means to press on the skin at said hair, and means coacting with and movable with respect to the first mentioned means to retract the tweezers.
18. In combination, a tweezers, skin stretching means, and means actuated toward the skin to cause said stretching means to function.
19. In combination, a support for a device to act on a particle on a skin, and skin stretch-
- ing means including relatively movable jaws associated with said support to space said device from the skin, said device being floatingly mounted on the support.
20. In mechanism of the character described, a device to remove a particle from a skin, means to contact said skin, and adjustable means coacting with said device and the first mentioned means to space said device at any desired distance from said skin.
21. Mechanism comprising skin stretching means having jaws movable apart, a device to remove a particle from said skin, means coacting with said device and the first mentioned means to actuate same as a unit, and means to actuate said device separately.
22. In a device of the character described, a mechanism for removing a particle from a skin, means for pressing on said skin, and a support for said device and said means, said support including jaws movable apart, said device being floatingly mounted on said support.
23. A device of the character described, including a tweezers of U-form, a support for the tweezers of U-form, said support being adapted to rest on the skin and stretch the same, and means interconnecting the tweezers and the support at the crotch of each.
24. A device of the character described, including a tweezers, a support for the tweezers having a plurality of arms adapted to rest on the skin with the jaws of the tweezers spaced from the skin, said arms being movable apart at an angle to stretch the skin and lower the tweezers toward the skin.
25. A device including a tweezers, a support for the tweezers having a plurality of arms adapted to rest on the skin, said arms being movable apart to stretch the skin, and a ring on the support having cam coaction with the sides of the tweezers, said ring being rotatable about the axis of the tweezers to close the same by the cam coaction aforesaid.
26. A device including a tweezers, a support therefor, said tweezers and support being both of U-form, means interconnecting the tweezers and the support at their crotches, said means including resilient means causing the tweezers to be floatingly mounted on the support, the arms of the support resting on the skin and being movable apart to stretch the skin.

In testimony whereof I affix my signature.

FRANCIS J. DOWLING
